DESIGN FOR A MICROPROJECTOR

Gustave Fassin, Irondequoit, N. Y., assignor to
Bausch & Lomb Optical Company, Rochester,
N. Y., a corporation of New York

Application March 30, 1934, Serial No. 51,251

Term of patent 7 years

To all whom it may concern:

Be it known that I, GUSTAVE FASSIN, a subject of the King of Belgium, and a resident of the town of Irondequoit, county of Monroe and State of New York, have invented a new, original, and ornamental Design for a Micro-Projector, of which the following is a specification, reference being had to the accompanying drawing, forming a part hereof.

Fig. 1 is a side view of a micro-projector embodying my new design.

Fig. 2 is a top plan view thereof.

Fig. 3 is an end view thereof.

I claim:

The ornamental design for a micro-projector substantially as shown.

GUSTAVE FASSIN.
